REFRIGERATING APPARATUS AND METHOD

Walter E. Carpenter, Belmar, N. J., assignor, by direct and mesne assignments, to McCabe Maier Corporation, Newark, N. J., a corporation of New Jersey

Application September 10, 1931, Serial No. 562,002

11 Claims. (Cl. 62—91.5)

My present invention is concerned with the provision of apparatus for and methods of efficiently utilizing solidified CO₂ or equivalent material for refrigerating purposes.

5 An object of the invention is to provide a method and apparatus which will be effective to maintain a uniform temperature in a refrigerated compartment where the intensely cold solid CO₂ is used either directly or through secondary 10 heat transfer media to absorb the heat from the compartment.

A more specific object of the invention is to provide a refrigerating system using solid carbon dioxide as the primary refrigerating medium and 15 in such a manner that the continuously dwindling size of the ice block will have no effect upon the uniformity of temperature in the refrigerating compartment. In other words, assuming that a fifty pound block of ice is originally introduced 20 into the system, the temperature of the refrigerated compartment will remain the same even when the ice has melted down to a pound or less.

Another object of the invention is to prevent 25 waste of a relatively expensive refrigerating medium, such for instance, as solid carbon dioxide. Concerning this object of the invention, it may be noted that refrigerated truck bodies when standing over night in a garage or other storage space, should be kept cold and it 30 has been common practice where solid CO₂ refrigerant has been used, to effect refrigeration of the truck not only during running but during storage by the CO₂.

In accordance with my invention, I provide 35 means whereby the refrigerating effect of the carbon dioxide ice is used to maintain the truck properly cooled during the day and at night the brine circulating pipes of the truck may be hooked up directly to an ammonia plant at the 40 factory in such a manner that any substantial sublimation of the ice is prevented and refrigeration is effected through the cheaper medium of the cold brine from the ammonia system.

Another object is to provide apparatus and 45 methods of the general character noted above which will be effective to hold an extremely close range of temperature within the refrigerated body without permitting the temperature to become unduly low and designed to quickly lower 50 the temperature when the system is called upon to temporarily absorb an unusual amount of heat.

Another object of the invention is to provide a 55 system of this character which, save for the manual charging of the carbon dioxide com-

partment, will be fully automatic in operation and will require the use of only simple types of conventional control mechanism and regulating devices.

Another object is to provide apparatus of 5 simple, practical construction which will be rugged and durable in use, both the apparatus and the methods being suitable for the solution of refrigerating problems regardless of the size of the chamber to be refrigerated, and operative to 10 maintain substantially uniform temperatures in any chamber from the size of a domestic ice box to the size of a freight car.

Another object is to provide refrigerating 15 methods which will permit any desired temperature from sub-zero Fahrenheit to above freezing point Fahrenheit to be uniformly maintained by a refrigerating agent which is itself intensely cold, solid CO₂ which sublimes at approximately 116° below zero Fahrenheit, being typical of the 20 tremendous difference in temperature of the primary refrigerating agent and the atmosphere of the chamber to be chilled.

In accordance with one embodiment of the invention, I provide a chamber for the solid CO₂ 25 which is insulated to prevent heat exchange by radiation between the CO₂ and the chamber to be refrigerated except through a support member of high heat conductivity upon which the CO₂ rests. This support member absorbs heat from 30 the chamber to be refrigerated either directly or through the intermediacy of a suitable secondary heat transfer medium, such for instance, as a closed brine circulating system. Where the heat 35 exchange between this conductive cold plate and the cooled chamber is direct, I find that by proportioning the area of the cold plate and by connecting it to any desired number of supplemental radiating surfaces designed in accordance 40 with the particular refrigerating requirements of the chamber to be cooled, any desired temperature may be maintained. I have discovered that the ice will be self-feeding in that it will burn off from the bottom directly against the support 45 means with substantially no diminution in cross sectional area and will be effective to absorb the required amount of heat until substantially the very last bit of the ice has been melted.

While an apparatus such as that above discussed, represents an elementary form of the invention, I preferably utilize various refinements of the apparatus, such for instance, as automatic means for insulating the bottom of the ice cake from the cold plate to prevent over refrigeration, and for automatically moving the ice back into 55

contact with the cold plate when heat is to be absorbed.

I have furthermore provided in conjunction with this apparatus a secondary heat transfer medium, such for instance, as brine pipes which under normal conditions are cooled directly by the solidified CO₂. Such a piping system, when used in conjunction with a truck or the like, is preferably so valved that heat transfer between the brine and the solid CO₂ may be cut off at night, and the cold brine from an ordinary ammonia plant circulated through the pipes by simply attaching a pair of hose connections from the ammonia plant into suitable taps in the truck piping system.

One method of insulating the ice from the cold plate as the temperature of the compartment to be refrigerated reaches the desired minimum, is an automatically operated elevator for picking up the ice bodily and lifting it out of contact with the plate. Various thermostatically controlled mechanical devices may be employed in the actuation of the elevator, and if desired, the pressure of the gas evolving from the ice itself may furnish the power for actuating the lift.

The invention may be more fully understood from the following description in connection with the accompanying drawings, wherein

Fig. 1 is a vertical sectional view through an ice receiving compartment embodying the invention;

Fig. 2 is a top plan view of the compartment with the cover removed;

Figs. 3 and 4 are perspective views showing modified forms of heat exchange plates;

Fig. 5 is a view partly in side elevation but principally in vertical section showing the container forming part of a thermostatically regulated cooling system and utilizing the CO₂ gas which evolves from the ice to supply the power necessary for moving the ice out of contact with the cold plate;

Fig. 5a is a fragmentary view mainly in vertical section illustrating another method of control in which the auxiliary cold plates are thermostatically moved into and out of conductive relationship to the bottom of the casing;

Fig. 6 is a fragmentary vertical sectional view through the bottom of the ice compartment illustrating an alternative method of operating the ice lift;

Fig. 7 is a vertical sectional view illustrating another type of control apparatus for actuating the ice elevator, this view being highly diagrammatic insofar as the illustrating of the regulating mechanism is concerned;

Fig. 7a is an enlarged schematic view of the switch mechanism 70 but showing the switch at right angles to the position illustrated in Fig. 7. Inasmuch as this switch is of entirely conventional character, most of the structural details thereof, such as the energy storing spring and the switch arm tripping and stopping mechanism have been omitted for the sake of clarity.

Fig. 7b is a sectional view through the switch mechanism taken approximately on the line 1a—1a of Fig. 7a.

Fig. 7c is an enlarged side elevational view of the cam 63;

Fig. 8 is a perspective view of one form of elevator which may be utilized;

Fig. 8a is a perspective view illustrating a modified type of elevator;

Fig. 9 is a view partly in section and partly in elevation showing the manner in which the CO₂

chamber may be associated with the ice freezing trays of an ordinary domestic ice box;

Fig. 10 is a transverse sectional view through a truck body illustrating an alternative type of refrigerating system in which the heat transfer between the solid CO₂ and the chamber to be cooled is effected through a secondary heat transfer medium;

Fig. 11 is a diagrammatic view of a generally similar system but illustrating the control mechanism for the pump and means for cutting off heat exchange between the CO₂ and the refrigerating compartment and circulating brine from an ammonia plant during storage periods of the truck.

Referring first to Figs. 1 and 2 of the drawings, I have shown a CO₂ container C, constructed in accordance with one form of the invention. This container has side walls 10 of good heat insulating material and is provided with a cover 11, also of heat insulating material, the cover 20 being removable to permit charging of the container with a block of CO₂ ice. The container bottom is formed of material which is highly heat conductive, such for instance as the relatively heavy cast aluminum plate 12, this plate defining an upwardly facing shoulder 13 upon which the sides of the container rest, the insulated side walls being secured as at 14 to the cold plate 12. With this type of construction, the ice is substantially insulated against heat exchange by radiation with the outside of the compartment, except through the cold plate 12 and in use, the ice will burn off at the bottom as it absorbs heat from the cold plate. In this figure, I have not shown any means of controlling the gas which is evolved upon sublimation of the solidified CO₂. This gas may escape from under the cover 11, although in practice, it is customary to deliver the cold gas into the compartment to be refrigerated. The rate of sublimation of the solid carbon dioxide will be directly proportional to the heat transmitted to it through the plate 12, which will offer an unchanging cold surface to the compartment to be refrigerated, regardless of the amount of solid carbon dioxide which is resting upon the 45 plate. The solid CO₂ sublimates at a rate directly proportional to the rate of heat absorption by the plate 12 and whether the ice piece be large or small, the temperature of the plate 12 will remain uniform and the temperature of the 50 chamber which is chilled by the plate, will likewise remain uniform. The frosting and defrosting of the plate will automatically prevent over refrigeration or under refrigeration.

In discussing uniformity of temperature, I of course, imply the maintenance of temperature within a very close range. Obviously the temperature of the compartment may be suddenly raised by the influx of warm air, but in such an event, the rate of sublimation of the CO₂ is almost instantly increased and the temperature of the compartment brought back to normal. In Figs. 1 and 2 I have not shown the compartment to be refrigerated but it will be understood that this compartment may be of any desired size and shape and the container may be disposed at any suitable location therein. When used in connection with a truck or freight car, the cover 11 of the ice compartment preferably is in the nature of a hatch in the roof of the truck or car through which the ice may be introduced.

In predetermining the heat absorbing area of the plate 12, I may resort to the use of any suitable number of additional cold plates in intimate contact with the plate 12 and serving to increase

the effective cold surfaces which are in heat exchanging relationship with the air within the chamber to be refrigerated.

In the present instance, I have illustrated supplemental cold plates 15, spaced from the side walls of the container and having their lower ends bolted or otherwise secured as at 16 to the laterally projecting bottom portion of the casting 12. Plates 15 are bolted, welded or otherwise tightly secured against cold plate 12 to promote good heat conductivity, and in practice, the supplemental plates 15 are kept at a temperature which is substantially identical with that of the plate 12. Frosting of the plate occurs uniformly over the exposed surfaces of the plate 12 and the plates 15. The number of the plates 15 used and the area thereof, is proportioned in accordance with the refrigerating requirements of the particular chamber to be chilled and in accordance with the temperature at which the chamber is to be maintained.

In Fig. 3 I have illustrated a slightly modified type of supplemental cold plate 15a which is provided with fins 17 thereon to increase the heat absorbing surface area.

In Fig. 4 I have shown another modified form of supplemental heat exchange plate 15b adapted to promote the circulation of air in the refrigerated compartment. The plate in this instance, is in the form of a louvre having a number of openings 18 therein with the projecting air current directing hood portions extending forwardly and outwardly over the openings.

In Fig. 5 I have illustrated a refrigerating system employing substantially the same type of container C' as that illustrated in Fig. 1. Here, however, the container cover 20 is clamped in place and a pop valve 21 is mounted in the cover to prevent the generation of unduly high gas pressures in the chamber. A mounting plate 22 is fixedly secured in any desired manner, not shown, below the chamber C' and one end of this plate serves as the rigid bottom of a diaphragm chamber, the chamber being completed by a flexible diaphragm 23, the edges of which are bolted down against one end of the plate 22, illustratively by the bolts 24, urging the clamping ring 25 against the edges of the diaphragm. In this case, a suitable recess 26 is provided in the upper surface of the cold plate casting 27, which constitutes the bottom of the chamber C', this recess normally accommodating an elevator platform 28 mounted on the upper end of a lifting rod 29, the latter having a threaded lower end 30 secured to the reinforced center of the diaphragm 23, as by a nut 31. Under normal conditions the gas evolving in the chamber C' passes outwardly through a passage 32 in the cold plate and through a flexible tubing 33 into the diaphragm chamber, from whence it escapes through an exhaust pipe 34.

A bellows type thermostat 35 has one end fixed to a bracket 36 attached to the under surface of the plate 32. A needle valve 37 adapted for cooperation with a valve seat 38 at the end of the exhaust pipe 34 is provided with a stem 39 extending through the thermostat and attached to the free end thereof as at 40.

The operation of this system is as follows:— Under normal conditions, the ice rests directly on the cold plate and the chamber to be refrigerated is cooled directly by the cold plate 27 and the supplemental plates 15. The gas which evolves upon sublimation of the ice, escapes into the diaphragm chamber and through the exhaust pipe 34,

discharging into the the chamber to be refrigerated and aiding to cool the same. Whenever the temperature of the chamber to be refrigerated is sufficiently lowered, the thermostat 35 contracts, moving the needle valve 37 into position 5 to close the exhaust pipe. Thereupon gas pressures start to build up in the diaphragm chamber and the diaphragm is moved upwardly, raising the elevator platform 28 through the lift rod 29, so that the block of solidified CO₂ is picked up off the cold plate and substantially insulated therefrom by the gas which surrounds the block. It will be apparent that the same pressure obtains in the chamber C' as the pressure which obtains in the diaphragm chamber, but the elevator itself, as well as the ice being under balanced pressures, are lifted by the effective unbalanced pressure applied over the surface of the diaphragm.

When the elevator is in raised position, it will 20 be obvious that there is no escape for the gas except through the pop valve 21. This valve, however, opens only under a relatively high pressure, so that if the needle valve 37 remains closed for a considerable period of time, valve 25 21 will merely open momentarily to blow off excessive gas pressures without releasing the pressure in the diaphragm chamber sufficiently to permit the elevator to drop under the weight of the ice thereon.

As soon as the refrigerated chamber starts to warm up again, the needle valve 37 is thermostatically withdrawn, thereby relieving pressure in the diaphragm chamber and permitting the elevator with the ice which it supports, to 35 again drop into contact with the cold plate 27, whereupon the rate of ice sublimation will be accelerated and the same cycle of cooling the chamber and thermostatically closing the needle valve repeated.

In Fig. 5a I have illustrated another method of thermostatically regulating the rate of sublimation of the solidified CO₂. In this case, instead of attempting to bodily elevate the ice from the primary cold plate, I utilize mechanism for automatically moving the auxiliary plates 15d, out of engagement with the primary cold plate 12d.

The cold plates 15d in this instance, have their upper edges hingedly connected as at 120 with 50 the heat insulating side walls 121 of the CO₂ container. The lower edges connected as at 122 to the outer ends of toggle levers 123, these levers having their inner ends pivotally connected to a spider element 124 having a hollow hub 55 which slides upon a pin 125 projecting downwardly from the cold plate 12d. The spider member 124 which actuates the toggle levers, is moved back and forth upon its mounting pin 125 by a thermostatic bellows 126 connected by 60 a push pull rod 127 with the spider.

The modus operandi of this type of control mechanism is as follows:—

When the temperature of the chamber to be refrigerated falls below a predetermined minimum, the contraction of the thermostatic bellows acts through the push pull rod 127 to elevate the spider 124, tending to straighten out the toggle levers 123 and to swing the lower ends of the plates 15d out of heat conducting relationship with the primary cold plate 12d, thereby reducing the effective heat absorbing area available for refrigerating the chamber. When the temperature again rises, the expansion of the bellows is effective to move the toggle levers 75

toward collapsed position and to thereby draw the lower ends of the auxiliary cold plates 15d into closed heat conducting relationship with the primary cold plate 12d.

5 Fig. 6 shows a simple arrangement for operating an ice elevator 41. Here the lifting rod 42 of the elevator passes through the cold plate 43 and has its lower end secured to a cross frame or plate 44. A coiled contractile spring 45 encircles the rod 42, one end of this spring being anchored as at 46 to the cold plate and the other end of the spring being anchored as at 47 to the plate 44 so that the normal tendency of the spring is to draw the plate 44 upwardly and 10 maintain the elevator 41 off the floor of the container. A circular bellows type mercury thermostat 48 is mounted on the plate 44, encircling rod 42 and its spring 45. The bellows tends, when expanded by heat, to force the plate 44 downwardly against the action of the spring 45 and thereby let the solidified CO₂ come to rest upon the cold plate. In order that the thermostat 48 may be substantially unaffected by direct contact with the cold plate, it preferably carries a 15 circular protective plate 49 of heat insulating material for engagement with the cold plate.

The cycle of operation of this form of apparatus is as follows:—When the temperature of the chamber to be refrigerated is above the temperature desired, the bellows 48 will depress the elevator 41 and drop the solid CO₂ against the cold plate, which in this instance, I have designated as 21a. When sub-normal temperatures obtain in the chamber to be refrigerated, the 20 contraction of the bellows will permit the spring 45 to lift the elevator 41, thereby moving the CO₂ out of contact with the cold plate and retarding its rate of sublimation.

In Fig. 7 I have shown an alternative type of 25 control system in which the elevator 60 may be moved up and down by mechanism operated from a thermostatically controlled motor. Here the plunger rod 61 of the elevator carries a roller 62 at its lower end, resting upon a cam 63 carried by cam shaft 64 driven through a suitable reduction gearing 65 from an electric motor 66. The motor may be energized from the usual storage battery 67 of a truck, the truck being fragmentarily illustrated at 68 in this view, and the cover 69 of the CO₂ compartment is in the form of a hatch in the roof of the truck. Arranged in the motor circuit is a standard four pole or 30 double two pole two-way snap switch 70 arranged to revolve with the cam shaft. This switch is controlled by a four point, double ended tilting mercury switch 71, which is also of conventional construction and is merely diagrammatically illustrated. The mercury switch is tilted back and forth by a lever train 72 actuated from a thermostatic bellows 73. In operation, the two pairs of arms 74 and 75 of the snap switch are laterally offset with respect to each other as are their respective pairs of contacts 74a and 75a.

The arms 74 and 75 are movable one-quarter turn at a time by the use of a conventional storage spring and arm detent and check mechanism which is not herein illustrated inasmuch as the switch itself is standard construction and the switch, per se, is not my invention. The 35 contacts for the arms 74 and 75 are so arranged that whenever one arm is moved into neutral position, the other arm is moved to bridge its two contact points.

75 The manner of operation of the device will

be apparent from Figs. 7a and 7b. From this position, it will be noted that the four point mercury switch 71 has been tilted in a counter-clockwise direction and that the motor circuit has been completed through the contact members 75a, 75a. After the motor has turned one-quarter of a revolution and thereby elevated the lift 60 through one of the high sides of the cam 63, the snap switch mechanism will switch the arm 75 to a neutral position and swing the switch 10 arm 74 into the contact bridging position of Fig. 7a. No motor circuit, however, can be completed through the arm 74 due to the fact that the mercury switch 71 is at this time open-circuited. When the mercury switch is again 15 thermostatically tilted to establish a circuit to the motor through the switch arm 74, the motor will again make one-quarter turn, permitting the lift 60 to drop as one low side of the cam passes thereunder and upon the completion of the one-quarter turn of the cam shaft 64, switch arm 74 will snap to a neutral position while the switch arm 75 snaps into position to bridge its contacts. At this time, however, the motor circuit is again 20 opened at the thermostatic switch and it will not be closed until such time as the necessary temperature variation in the chamber to be refrigerated has acted through the thermostat to again tilt the mercury switch.

In other words, when the thermostat 73 contracts and shifts the mercury switch 71 in one direction, it will close the motor circuit through the four pole or double two pole, two-way snap switch and the motor will run until the cam shaft 64 has made one-quarter revolution, whereupon 35 the snap switch will cut out and further operation of the motor is prevented until the thermostatic switch 71 is tilted in the opposite direction under the influence of the thermostatic bellows, whereupon the motor will again be cut into circuit and the cam shaft advanced another quarter revolution. It will be seen from the side view of the cam (Fig. 7c) that one quarter revolution of its shaft is sufficient to cause it to either raise or lower the elevator as the case may be. Obviously, the elevator is raised upon contraction of the bellows 73 and lowered upon the expansion thereof.

Fig. 8 shows in perspective the elevator 60 which is of generally star shape in order to afford 40 adequate surface contact with the ice. The elevator which is of heat conducting material, fits very snugly into its recess 60a in the cold plate so that when the elevator is lowered, it is in intimate heat exchange relationship with the cold plate and the desired burning off of the ice block bottom is effected. Fig. 9 shows an alternative 45 form of elevator 160, which is of square cross section.

Fig. 9 is a somewhat diagrammatic view showing one of my casing units C, having its cold plate directly attached to a hanger unit 80, mounting a plurality of shelves 91 in which freezing trays 92 for ice cubes, are supported.

In Fig. 10 I have shown the invention as applied to another and somewhat modified embodiment of the invention used for refrigerating a truck body B. Here the ice chamber C² has a cover 100 in the form of a hatch-way in the roof of the truck and the cold plate 101 is in the form of a hollow casting connected at opposite sides with the two ends of a closed piping system 102 containing brine. It is within 50 the scope of my invention to employ a thermo-

siphonic brine circulating system in which event, all of the brine pipes would be below the points of connection of the piping system to the hollow cold plate. In the present case, I have 5 shown a brine circulating pump 103 forming part of the system and operated in any suitable manner to maintain a continuous or intermittent brine circulation. The regulating devices and the actuating means for this pump are not illustrated in Fig. 10, but it may be conveniently operated in the same manner as the pump which I have shown in connection with the disclosure of Fig. 11, which I shall now describe.

With this form of the invention, the ice compartment C³ is completely insulated and a closed system of piping 105 includes pipe coils lying within the bottom of the chamber C³ and upon which the block of CO₂ rests. The piping within the chamber C³ may, if desired, be provided 10 with fins 105a or its effective heat exchange area 20 may be otherwise increased. At each side of the pipe coil which lies within the chamber C³, I provide a shut off valve 106 and when these valves are closed, a partial brine circulation may 25 be maintained by tapping in an inlet line 107 and an outlet line 108 through suitable extensions 109 arranged at spaced points in the piping system 105 and normally closed by suitable 30 valves 110. When the valves 106 are closed and the valves 110 opened, and the hose connections 107 and 108 from an ordinary ammonia plant hooked on to the system, it will be observed that 35 there will be substantially no sublimation of the CO₂ ice since this ice is housed in a completely insulated chamber and no brine can circulate in that section of the piping system 105 which is arranged between the valves 106. Thus a truck standing idle at night, may be hooked up to an ordinary ammonia plant and kept cool while the 40 expensive CO₂ refrigerant is substantially preserved against doing any work. When the truck is running during the day delivering ice cream or other frozen commodities, the valves 110 are closed, the hose connections 108 and 107 removed and the valves 106, 106 opened. Even in 45 the absence of a circulating pump, there would be a thermo-siphonic circulation of brine chilled by the intimate contact between brine pipes within the refrigerating chamber and the solid 50 CO₂. Such a thermo-siphonic circulation would be effective to maintain a substantially uniform temperature in the truck body due to the cold storing ability of the brine. An even more accurate regulation, however, may be effected by 55 the use of a circulating pump 111 disposed at a suitable point in the piping system 105. This pump is actuated by an electric motor 112, operated from the usual storage battery 113 of the truck. The motor is cut in and out of circuit 60 by a thermostatic switch 114 so that when the body of the truck has been cooled to the desired temperature, thermostatic switch 114 will open, cutting out the motor and stopping the pump at which time the brine due to the presence of 65 the pump 111, which substantially prevents thermo-siphonic circulation thereof, will be substantially quiescent in the pipes and there will be substantially no heat delivered to the CO₂ ice. If the truck body starts to warm up, the 70 thermostatic switch 114 can close, cutting off the motor and operating the pump so that the brine is circulated through the chamber C³ and the heat which has been absorbed by the brine, is quickly absorbed by the CO₂.

75 I refer to brine in its most generic sense, it

being merely necessary to provide some solution which will not be frozen in the pipes by the solid CO₂ and which has a cold storing property. One advantage of using a brine, particularly a brine of the same character commonly used in an ammonia plant, is the fact that there is no need for draining the brine systems when hooking up the connections 107, 108, that is to say, the brine circulating pipes of an ammonia system may be hooked directly on to the brine 10 circulating pipes of the truck system with a minimum amount of trouble and effort.

It will be observed that in many of the various systems illustrated, I have omitted all showing of supports for the control mechanism and 15 all means for utilizing the refrigerating effect of the CO₂ gas. In practice, however, this gas will be directly or indirectly vented into the chamber to be cooled so that the maximum refrigerating value of the ice may be utilized. Entirely regardless of the manner in which the gas 20 exhaust is handled, all forms of the invention provide means for most effectively obtaining direct or indirect heat interchange between the intensely cold CO₂ ice and the chamber to be chilled 25 and in every event, unnecessary waste of the ice and over refrigeration of the chamber is prevented.

It is within the scope of my invention to utilize various intensely cold refrigerating mediums 30 other than solidified CO₂ and I intend that the term "solid CO₂" shall be construed as embracing all refrigerants which are equivalent for purposes of the present invention. Water ice does not come within this classification since the 35 maximum refrigerating temperature obtained therefrom would be wholly insufficient for the purposes of this invention.

It will thus be seen that there is herein described apparatus and methods in which the several features of this invention are embodied, and which apparatus and methods in their action, attain the various objects of the invention and are well suited to meet the requirements of practical use.

As many changes could be made in the above construction and many apparently widely different embodiments of this invention could be made without departing from the scope thereof, it is intended that all matter contained in the above 50 description or shown in the accompanying drawings shall be interpreted as illustrative and not in a limiting sense.

Having thus described my invention, what I claim as new and desire to secure by Letters 55 Patent is:—

1. A method of refrigeration which consists in depositing a substantially solid block of carbon dioxide upon a support means of high heat conductivity and preventing heat exchange between 60 said block and the region to be refrigerated except through said conductive means, and automatically reducing the rate of heat exchange between said means and the block, by lifting the block out of engagement with said means when 65 the temperature of the region to be refrigerated has been reduced to a predetermined extent.

2. Refrigerating apparatus of the class described including a container for solid carbon dioxide, said container being completely insulated except at the portion thereof which sustains the carbon dioxide, said sustaining means being of high heat conductivity and in heat exchange relationship with the region to be refrigerated, whereby sublimation of the CO₂ occurs 70 75

substantially entirely at the surface of the CO₂ which is in contact with said conductive means, means for breaking the contact between the CO₂ and the conductive means when the temperature 5 of the refrigerated region has been reduced to a predetermined point and means for re-establishing the contact when the temperature has increased to a predetermined point, said making and breaking means including an elevator adapted to 10 lift solid CO₂ off its support and mechanism to actuate the elevator and a thermostat for controlling said mechanism.

3. Refrigerating apparatus of the class described including a container for solid carbon dioxide, said container being completely insulated except at the portion thereof which sustains the carbon dioxide, said sustaining means being of high heat conductivity and in heat exchange relationship with the region to be refrigerated, 15 whereby sublimation of the CO₂ occurs substantially entirely at the surface of the CO₂ which is in contact with said conductive means, means for breaking the contact between the CO₂ and the conductive means when the temperature of the 20 refrigerated region has been reduced to a predetermined point and means for re-establishing the contact when the temperature has increased to a predetermined point, said making and breaking means including an elevator adapted to lift 25 solid CO₂ off its support and mechanism to actuate the elevator and a thermostat for controlling said mechanism, said mechanism including an elevator operating means, said means including an expansible shell through which the gas sublimating from the CO₂ is normally exhausted and a thermostatically controlled valve for closing the 30 exhaust and permitting the CO₂ gas pressure in the chamber to actuate the elevator.

4. Apparatus of the character set forth in 40 claim 3 and wherein a safety blow-off valve is provided in the solid CO₂ container to relieve unduly high gaseous pressures when the thermostatically controlled valve is closed.

5. Apparatus of the character set forth in 45 claim 3 and wherein a safety blow-off valve is provided in the solid CO₂ container to relieve unduly high gaseous pressures when the thermostatically controlled valve is closed, said safety valve operating only at pressures in excess of 50 those required to actuate the elevator.

6. Refrigerating apparatus of the class described including a container for solid carbon dioxide, said container being completely insulated except at the portion thereof which sustains the 55 carbon dioxide, said sustaining means being of high heat conductivity and in heat exchange relationship with the region to be refrigerated, whereby sublimation of the CO₂ occurs substantially entirely at the surface of the CO₂ which is in contact with said conductive means, means for 60 breaking the contact between the CO₂ and the conductive means when the temperature of the refrigerated region has been reduced to a predetermined point and means for re-establishing 65 the contact when the temperature has increased to a predetermined point, said making and breaking means including an elevator adapted to lift solid CO₂ off its support and mechanism to actuate 70 the elevator and a thermostat for controlling said mechanism, the actuating mechanism including a motor operated cam and a switch for

the motor and a thermostat to actuate the switch.

7. Refrigerating apparatus of the class described including a container for solid carbon dioxide, said container being completely insulated except at the portion thereof which sustains the 5 carbon dioxide, said sustaining means being of high heat conductivity and in heat exchange relationship with the region to be refrigerated, whereby sublimation of the CO₂ occurs substantially entirely at the surface of the CO₂ which is 10 in contact with said conductive means, operating means including a spring normally operated to lift the elevator and a thermostat including temperature sensitive apparatus to oppose the action of the spring when the temperature in the refrigerated region exceeds a predetermined minimum. 15

8. A method of refrigeration which consists in cooling a chamber to be refrigerated by heat exchange between said chamber and an encased 20 supply of solid carbon dioxide through the intermedias of a highly heat conductive support for the encased carbon dioxide and utilizing the temperature of the compartment to be refrigerated to regulate the rate of heat exchange between the solid carbon dioxide and the support, by lifting carbon dioxide bodily off its support when the temperature of the chamber to be refrigerated is reduced to a predetermined minimum. 30

9. In a refrigerating apparatus of the character described, a container for solidified CO₂, said container including CO₂ support means of high heat conductivity and adapted for disposal in heat exchange relationship with the chamber to 35 be refrigerated, means substantially preventing heat exchange by radiation between the CO₂ and the chamber to be refrigerated except through said support means, complementary heat absorbing means movable into conductive relationship 40 with said support member and means thermostatically controlling the movement of the secondary heat absorbing means into and out of such conductive relationship with said support member. 45

10. Apparatus as set forth in claim 9 wherein the support means comprises a metal plate serving as the bottom of the container and the secondary heat absorbing means including metallic members arranged exteriorly of the container and 50 movable into and out of engagement with the plate.

11. In a refrigerating apparatus of the character described, a container for solidified CO₂, said container including CO₂ support means of 55 high heat conductivity adapted for disposal in heat exchange relationship with the chamber to be refrigerated and constituting a primary means for absorbing heat from said chamber to be refrigerated, means substantially preventing heat exchange by radiation between the CO₂ and the chamber to be refrigerated, except directly through said support means, a secondary heat absorbing means disposed within the chamber and capable of transmitting heat to said CO₂ 60 only through said support means, and means thermostatically operable to effect relative movement of said primary and secondary heat absorbing means into or out of conductive heat exchange relationship with each other. 65
